Primary Examiner — Mimosa De

(57) **CLAIM**

The ornamental design for reconfigurable seats for automotive vehicle, as shown and described.

DESCRIPTION

FIG. 1 is a front-perspective view of reconfigurable seats for automotive vehicle, in an upright position, of the new design;

FIG. 2 is a top thereof, in the upright position;

FIG. 3 is a side view thereof, in the upright position;

FIG. 4 is a front view thereof, in the upright position;

FIG. 5 is a side view thereof, opposite that of FIG. 3, in the upright position;

FIG. 6 is a rear view thereof, in the upright position;

FIG. 7 is a front-perspective view thereof, in a downwardly folded and stowed position; and,

FIG. 8 is a side view thereof, in the downwardly folded and stowed position.

The broken and dashed lines form no part of the claimed design.

1 Claim, 8 Drawing Sheets
